UNITED STATES PATENT OFFICE.

WILLIAM W. ALEXANDER, OF DENVER, COLORADO; EDWARD T. KEIM, ADMINISTRATOR OF SAID ALEXANDER, DECEASED, ASSIGNOR, BY MESNE ASSIGNMENTS, TO THE PROTECTIVE SIGNAL MANUFACTURING COMPANY, A CORPORATION OF COLORADO.

CIRCUIT-CLOSING DEVICE.

1,077,948.

Specification of Letters Patent.

Patented Nov. 4, 1913.

Application filed February 21, 1911. Serial No. 609,893.

To all whom it may concern:

Be it known that I, WILLIAM W. ALEXANDER, a citizen of the United States of America, residing at Denver, in the county of Denver and State of Colorado, have invented certain new and useful Improvements in Circuit-Closing Devices, of which the following is a specification.

This invention relates to circuit closing devices for signaling apparatus and more particularly to instruments of the type shown and described in my applications for Patent Numbers 570,615 and 598,640 filed in the United States Patent Office respectively

15 on July 6, 1910 and December 21, 1910.

In the circuit closing instruments shown and described in the above applications, one vibratory bar, supported in a hermetically sealed casing, carries two contact-blades and 20 an interposed tongue which through the instrumentality of an appliance which retards the movement of the latter, are brought in contact during the vibratory movement of the bar.

25 It is the object of the present invention to simplify the construction of the above described instruments without deterioration to the practicability or effectiveness thereof, by the provision of two vibratory bars 30 which being mounted to vibrate along substantially parallel lines, have different degrees of vibratility and carry electric contacts one of which extends in the path of the other.

35 When, in the operation of my invention the equilibrium of the two elements is disturbed, they will, under the influence of forces of restitution, vibrate through amplitudes of unequal length, by reason of the 40 difference in their degrees of sensitiveness, with the result that, while in motion, they will repeatedly pass each other and thus bring the electric contacts in engagement to intermittently close the normally open electric circuit of which they are the terminals.

45 While my invention is adapted to be effectively employed for various purposes, it is more particularly designed for use in connection with a railroad track, to be actuated by the jarring motion of a passing train or engine, and audibly or visibly announce the approach thereof at a crossing, station or other remote point along the railway.

In the accompanying drawings, in the

various views of which like parts are similarly designated, the casing which incloses the mechanism comprised in my invention, is shown in section, Figure 1 representing a side elevation of the said mechanism and, Fig. 2 a plan view of the same.

55 Referring to the drawings by numerals, 2 designates the preferably cylindrical casing which may be provided with clamps 3 or other means for fastening it to a rail 4. The ends of the casing are hermetically 60 closed by means of heads 5 and 6 which are provided with binding screws, 7 and 8 to connect with the conductors of electricity of the circuit in which the signaling instrument is located. The two heads are insulated 65 from the casing 2 and they are constructed to conduct in connection with parts secured upon their inner surfaces, the electric fluid from the respective binding screws to the normally separated contacts which 70 are associated with the two vibratory elements 7' and 8' disposed within the casing.

75 The elements above referred to, are respectively composed of rigid bars 7^a and 8^a which carry at one of their extremities 80 poises 7^c and 8^c and whose opposite ends are attached to the ends of springs 7^d and 8^d which at their outer extremities are firmly secured upon a bridge 9 supported upon a flat bar 10, which, being connected with the 85 head 5, extends longitudinally through the casing and terminates in proximity to the opposite head 6. Three posts 12 erected upon the bar 10, respectively between and at 90 opposite sides of the members 7^a and 8^a, and connected at their upper ends by means of a cross-piece 13, are provided to guide the elements 7 and 8 during their vibratory motion.

95 To differentiate the degrees of vibratility of the two elements, the poises 7^c and 8^c are in the construction shown in the drawing, made to differ in weight but it will be readily understood that the same object may be 100 equally effectively accomplished by other means, as for example by reducing the length of one of the elements, by varying the position of one of the poises relative to the other or by providing springs 7^d and 8^d of different degrees of resiliency.

105 Rigidly secured upon the member 7^a of the element 7, is a contact 14 which by means of the said member, the correspond-

ing spring 7^a and the bridge 9 to which the latter is attached, is constantly maintained in electric communication with the head 5 and the therewith connected binding screw 5 7. The other element, 8, carries an insulated, preferably flexible, blade 15 which when the parts are in their positions of rest, extends in spaced relation above the contact 14, and which is connected with the head 6 10 and the corresponding binding screw by means of an insulated wire 16 which is laced through apertures in the bar 10, and which for clearness of illustration, has been represented in the drawings by a dash-dot line. 15 To limit the period during which the signaling instrument is actuated by the intermittent closing of the circuit in which it is located, a leaf-spring 17 is secured upon the bridge 9 at a point below the point of connection of the adjacent member 7^a of the more sensitive one of the two vibratory elements, the opposite end of the said leaf spring bearing against the under surface of the said member 7^a, to check its movement, 20 25 by sliding contact therewith.

When by a shock or jar imparted to the support with which the casing 2 is connected, the equilibrium of the two elements 7 and 8, is disturbed, their vibratory movements through arcs of different amplitude, 30 will cause them to repeatedly pass each other and thus bring the contacts 14 and 15 intermittently in engagement.

Having thus described my invention, what 35 I claim and desire to secure by Letters-Patent is:—

1. In a circuit closing instrument, two vibratory elements of different degrees of vibrability, and a contact blade on one of said 40 elements, extending in the path of the other element, the said blade and the last mentioned element being electrically connected with opposite sides of an electric circuit.

2. In a circuit closing instrument, two 45 vibratory elements of different degrees of vibrability, and electric contacts connected

respectively with the said elements, to engage during the vibratory movement thereof.

3. In a circuit closing instrument, two vibratory elements of different degrees of vibrability, an electric contact secured to 50 one of said elements, and a contact blade connected with the other element and extending in the path of the said contact to engage therewith during movement of the said elements. 55

4. In a circuit closing instrument, two vibratory elements of different degrees of vibrability, each including a rigid member, a resilient member, at one end thereof, and a poise at the opposite end of the same, the 60 two resilient members being supported at corresponding ends, to vibrate along substantially parallel lines, and normally separated electric contacts connected with the respective elements to engage during vibratory movement thereof. 65

5. In a circuit closing instrument, two corresponding vibratory elements, each including a rigid member, and a resilient member connected therewith at one of its 70 ends and supported at its opposite end, oppositely disposed electric contacts connected with the respective elements, and poises of different weights secured in corresponding positions upon the said rigid members. 75

6. In a circuit closing instrument, the combination with a casing adapted to connect with a suitable support, of two vibratory elements of different degrees of vibrability supported within the same, and electric contacts connected with the respective elements to engage during vibratory movement thereof, in electric communication with a circuit outside the said casing. 80

In testimony whereof I have affixed my 85 signature in presence of two witnesses.

WILLIAM W. ALEXANDER.
